(57) **CLAIM**

The ornamental design for a vehicle exhaust port mobile phone holder, as shown and described.

DESCRIPTION

FIG. 1 is a front perspective view of the vehicle exhaust port mobile phone holder;

FIG. 2 is a rear perspective view of the vehicle exhaust port mobile phone holder;

FIG. 3 is a front elevation view of the vehicle exhaust port mobile phone holder;

FIG. 4 is a rear elevation view of the vehicle exhaust port mobile phone holder;

FIG. 5 is a left side elevation view of the vehicle exhaust port mobile phone holder;

FIG. 6 is a right side elevation view of the vehicle exhaust port mobile phone holder;

FIG. 7 is a top plan view of the vehicle exhaust port mobile phone holder; and,

FIG. 8 is a bottom plan view of the vehicle exhaust port mobile phone holder.
